OR D 15,431

DESIGN.

L. K. FULLER.

ORGAN CASE.

No. 15,431.

Patented Oct. 7, 1884.

UNITED STATES PATENT OFFICE.

LEVI K. FULLER, OF BRATTLEBOROUGH, VERMONT, ASSIGNOR TO THE
ESTEY ORGAN COMPANY, OF SAME PLACE.

DESIGN FOR AN ORGAN-CASE.

SPECIFICATION forming part of Design No. 15,431, dated October 7, 1884.

Application filed May 31, 1884. Term of patent 14 years.

To all whom it may concern:

Be it known that I, LEVI K. FULLER, a citizen of the United States, and a resident of Brattleborough, Windham county, Vermont, 5 have invented or produced a new and original Design for an Organ-Case, of which the following is a specification.

My design is clearly shown in the accompanying photographic illustration, in which A 10 designates the front board of the case; B, the key-board projection above the front board; C, a strip above the key-board; D, the back board of the case, and E the ends.

The general configuration of the case resembles that of ordinary cabinet-organ cases, but 15 it differs from these in the particulars I will now set forth. The front board, A, is divided as usual into three panels, *a a a*, which are ornamented by linear patterns comprising as 20 to the middle panel a horizontal stripe, which divides the panel about equally, and as to the side panels two horizontal stripes and one vertical stripe, arranged to divide the panel into six substantially equal divisions. At the 25 crossings of the stripes are ornamental bosses, all as shown in the photograph. These stripes are composed each of several fine lines. The front of the key-board projection B is provided as usual with an open-work strip. This I form 30 of two elongated openings, *b b*, with rounded ends. Below these openings is a horizontal stripe formed of several fine lines. The strip C is composed of three sunk panels—namely, 35 a central circular panel, and two side panels which are elongated and have rounded ends. The visible portion of the back board, D—namely, that portion which rises above the ends E of the case—is divided into three panels, *c d d*, the central panel, *c*, rising above 40 the side panels, *d d*. The central panel is provided with a hood-like projection, *e*, at its top, the lower or pendent edge of which has an ornamental contour, while the top edge has a bead-like band. This central panel, *c*, is 45 also provided with a pocket-like projection at its base, the bars *g* across the front of which are beaded. Between the said bars are ornaments in the nature of double balls, and on the top bar appear ornaments in the nature 50 of single balls. The face of the panel *c* is

ornamented by a horizontal and a vertical band or stripe, the two arranged to divide the face into four substantially equal parts. These bands are formed of several fine parallel lines. The side panels, *d*, of the back 55 board are ornamented alike, and a description of one will suffice. Across the top of *d* is a horizontal band, *h*, and two stripes or bands composed of several fine parallel lines cross the panel diagonally, the crossing being ornamented by a boss, all as clearly shown in the photograph. In the angles where the side panels, *d*, join the center panel, *c*, are ornaments *i i*, which have a curved contour, and on the back corners of the case are vertical 60 corner ornaments, *jj*, with semicircular bosses. On each end of the case at its top is an ornament, *k*, which resembles a balustrade.

It will be seen that the unity of the design as to its elemental features is preserved by 70 giving to the openings *b* in the key-board projection a similar contour to the sunken panels of the design for strip C, and also by giving the bands or stripes and bosses on the panels of the front board, A, an appearance 75 and arrangement similar to those on the back board, D.

Having thus described my design, I claim as its novel features—

1. In an organ-case, the design which consists of the front board, A, divided into three panels, *a a a*, the middle panel divided into two substantially equal parts by a horizontal stripe composed of fine lines, and the side panels each divided into six substantially 85 equal parts by one vertical and two horizontal stripes, composed of fine lines, with bosses at the crossings of said lines, substantially as shown in the accompanying photograph.

2. In an organ-case, the design which consists of the two oblong openings *b b* in the front of the key-board projection, formed with rounded ends, and the strip C, above the key-board, provided with a central circular sunk panel, and two elongated sunk panels at its 95 sides, with rounded ends, substantially as shown in the accompanying photograph.

3. A design for an organ-case, having a back board, D, which rises above the ends of the case, divided into three panels, *c d d*, the 100

OVER

center panel, *c*, having a hood-like ornamental projection, *c*, a pocket-like projection at its base, ornamented as described, and a face ornamented with crossed strips composed of fine lines, and the like side panels, *d*, having each a top board, *h*, and diagonal cross stripes formed of fine lines, with a boss at their intersection, substantially as shown in the accompanying photograph.

10 4. In an organ-case, the design which consists of the elevated back board divided into three panels, *c* & *d*, having the ornamentation

and configuration substantially as shown, the corner posts, *j*, with semicircular bosses, and the baluster-like end ornaments, *k*, substantially as shown in the accompanying photograph. 15

In witness whereof I have hereunto signed my name in the presence of two subscribing witnesses.

LEVI K. FULLER.
